UNITED STATES PATENT OFFICE.

SOLON J. BOUGHTON, OF TOLEDO, OHIO, ASSIGNOR TO THE WILLYS-OVERLAND COMPANY, OF TOLEDO, OHIO, A CORPORATION OF OHIO.

STARTER CONTROL MECHANISM FOR GAS ENGINES.

Application filed July 3, 1924. Serial No. 723,989.

- The present invention relates to starter control mechanisms for gas engines, and has for one object to provide means for preventing the operation of the switch for closing the circuit of the starting motor while the engine is running, whereby to prevent moving of the starting pinion into engagement with the teeth of the fly-wheel, except when the latter is at rest.
- 10 Another object of the invention is to provide means under the control of the generator, adapted, as soon as the generator is started, to actuate means which will be effective to prevent the closing of the starter switch and which will hold the latter open until such time as the generator ceases to produce current.

Another object of the invention is to employ a circuit-breaker in a generator circuit which will become effective upon the starting of the generator, to actuate means adapted to prevent the closing of the starter switch while the engine is running.

Another object of the invention is to make use of a motor vehicle control device, such as a clutch release pedal, to become effective for closing the starter switch after moving to clutch releasing position, in combination with electromagnetic means for preventing the closing of said switch while the engine is running.

Other objects will appear from the description to follow, covering certain embodiments of the invention, which, for the purposes of the present application, I have illustrated in the accompanying drawings, in which:

Figure I is a diagrammatic view illustrating one embodiment of the invention.

Fig. II is a sectional elevation of my improved switch, taken on line II—II of Fig. III.

Fig. III is a sectional elevation taken substantially on line III—III of Fig. II.

Fig. IV is a sectional elevation taken substantially on line IV—IV of Fig. III.

Fig. V is a diagrammatic view illustrating a slightly modified form of the invention, and

Figs. VI and VII are diagrammatic views of still another slightly modified form of the invention, showing a single armature adapted to both control the generator circuit and to prevent the closing of the starter switch.

Similar reference characters refer to cor-

responding parts throughout the several views of the drawing.

In the diagrammatic views of the drawings, Figs. I and V, I have shown a generator 10 which is to be geared to an internal combustion engine (not shown), a battery 11, a circuit-breaker 12, an ammeter 13, and a starting motor 14 adapted to be thrown into driving connection with the engine, all of which are well-known in the art. A starting switch 15 of any desired type may be used, such as that shown in Figs. I and V, and in detail in Figs. II, III and IV.

The starting switch is preferably placed in position to be actuated by the clutch pedal 16, after the latter has been moved to clutch releasing position, though it may be mounted for movement independently of the clutch pedal. Closing of the switch is prevented while the engine is running, by an armature 17, preferably in the form of an angular-shaped lever pivoted intermediate its ends at 18, and normally held at inoperative position by a spring 19. In Fig. I, the armature is shown moved into position to prevent the closing of the switch, the same being moved by an electro-magnet 20, as soon as the generator is started by the engine, while in the modification shown in Fig. V, the circuit-breaker 12 is utilized to move the lever and accomplish the same result. The single coil of the electro-magnet 20 is preferably one of 85 comparatively heavy or low resistance wire. The armature 17 will be pulled up immediately upon the starting of the generator and before the circuit-breaker 12 in Fig. I is closed, the circuit then being from the generator, 90 through conductor 38, coil 20, conductor 39, low resistance coil of circuit-breaker 12, high resistance coil of circuit-breaker 12, and through ground back to the generator.

In Fig. V, the spring 19 is of such capacity 95 as to permit the armature to be pulled up by the core of the magnet immediately upon the starting of the generator and before the speed of the engine is increased sufficiently to cause the generator to close the circuit-breaker.

It will be seen that when it is desired to start the engine (not shown), the operator may first release the clutch by depression of the pedal 16, and that continued depression of the same will close the switch to start the 105 motor. The pedal then being released and

the engine started by the motor, the generator, which is geared to the engine, will begin operation, at which time the armature 17 will be thrown into position to prevent re-closing of the switch until such time as the engine has stopped running and the generator come to rest, whereby the electro-magnet, in either case, will be de-energized and the spring 19 allowed to return the armature to switch re-

leasing position.

The construction of the switch 15, which may be operated directly by the foot or through the clutch pedal, as shown, will now be described. The several parts of the switch 15 are enclosed in a casing comprising the upper and lower members 21 and 22, the former having an extension 23 in which is mounted the plunger 24 carrying the contact bar 25 on its lower end, which is adapted to be moved into engagement with the contact members 26, preferably in the form of binding posts, as shown in Fig. II, and to which the wires 27 are connected for completing the circuit between the motor and the battery through ground, as shown in Figs. I and V. The plunger 24 is normally held in the position shown in Fig. III by a spring 28, the upper end of which engages a depressible sleeve 29 telescoped over the extension 23, while the lower end of the spring rests upon a plate 30 carried by the upstanding portion 31 of the casing member 21. The contact member 25 is insulated from the casing and from the plunger by the plates 32 and 33 suitably connected with the plunger, as shown in Figs. II and III and formed of any suitable insulating material. The contacts 26 are insulated from the casing by the insulating plates 34 and 35, as shown in Fig. II.

The electro-magnet 20 for actuating the armature 17, is mounted within the switch casing, the spring 19 being interposed between the magnet and the outer end of the armature to normally hold the latter in the position shown in Fig. III, the armature being limited in its movement by a stop 36 connected with the casing. The ends of the coil of the magnet are connected to suitable binding posts 37 carried by the upper member 21 of the casing, the posts being also adapted to receive the ends of the wires 38 and 39, extending between the generator and circuit-breaker, as shown in Fig. I, the circuit-breaker being connected with the battery through the ammeter 13 by the wires 40 and 41, return being through ground, as indicated.

In the modification shown in Fig. V, the circuit-breaker is conveniently located at the point of the starting switch, thus making it possible to dispense with the electro-magnet 20 disclosed in Fig. I. The current in this case flows from generator to battery through wire 42, circuit-breaker 12, wire 43, ammeter 13 and wire 44 while the engine is running above a predetermined speed. At slower

speeds the current flows from the generator through both coils of the circuit-breaker and through ground back to the generator.

The upstanding portion of the armature 17 is provided with an insulating plate 45, which, when the armature is in the position shown in Figs. I and V, forms a stop for the switch contact plate 25 to prevent it from being depressed into engagement with the lower contact members 26.

In the modification disclosed in Figs. VI and VII, the arrangement is the same as that shown in Fig. V, except that a single armature 46 is adapted to both close the generator circuit and to prevent closing of the starter switch while the engine is running. In this modification, the armature 46 is normally in the position indicated by the dotted lines in Fig. VII, that is, before the engine is started. In this position of the armature, the starter switch 15 may readily be closed by depression of the pedal 16, whereby to start the motor 14. As soon as the engine is started by the motor, the generator, coupled with the engine, will begin operation. The initial speed of the engine at starting is not very great, but is sufficient to cause the generator to magnetize the coil of the circuit-breaker to such an extent that it will move the armature 46 from the dotted line position shown in Fig. VII, into engagement with the spring 47, but not far enough to cause the contact plate 48 of the armature to engage the contacts 49. However, in this position, the armature has been moved sufficiently far to prevent the closing of the starter switch 15. As the speed of the engine increases above a predetermined rate, the armature will be further pulled up by the magnet, against the action of the spring 47, until the contact plate 48 engages the contacts 49, as shown in Fig. VI, and will remain in this position until the speed of the engine drops below said predetermined rate. When the engine is stopped, the armature is returned to the dotted line position, preferably by a weight 50 located thereon at the left of the pivot-point 51 thereof. Thus, it will be seen that by the use of this construction, a saving in the number of parts can be effected, and a consequent saving in the cost of manufacture.

While I have shown in considerable detail, certain specific embodiments of my invention, it is to be understood that this showing and description are illustrative only, and that I do not regard the invention as limited to the details of construction illustrated and described, except in so far as I have included such limitations within the terms of the following claims.

I claim as my invention:

1. In combination, an electric control system for an explosive engine including a generator, a circuit-breaker operated by said generator and an electrically operated starter

having a normally open circuit, a switch for closing said circuit, and mechanical means actuated by said circuit-breaker upon the starting of the generator adapted to prevent the closing of the switch.

2. In combination, an electric starting motor for an explosive engine, a current supply source for the motor, a normally open circuit between the motor and supply source, a switch for closing said circuit, a generator geared to said engine, an electro-magnet in the connection between the generator and supply source, a clutch releasing member adapted to close said switch subsequent to its movement to clutch releasing position, and means adapted to be actuated by said electro-magnet whereby the movement of the clutch releasing member is reduced and the closing of the switch is prevented while the engine is running.

3. In combination in an automotive vehicle, an electric starting motor, a battery, a generator, electrical connections between said motor and battery and between said generator and battery, a circuit-breaker included in the connection between the generator and battery, a normally open switch in the connection between the motor and battery, a clutch releasing member movable to close said switch subsequent to its movement to clutch releasing position, and means adapted to be actuated by said circuit-breaker upon the starting of the generator, whereby the movement of the clutch releasing member is reduced and the closing of the switch is prevented while the engine is running.

4. In combination with an electric control system for an explosive engine including a generator, a circuit breaker connected thereto, an electrically operated starter having a normally open circuit, a manually operated switch for closing said circuit mounted adjacent said circuit-breaker, and means whereby the functioning of the circuit-breaker affects the mechanical operation of said switch.

5. In combination with an electric control system for an explosive engine including a generator and a generator circuit, an electro-magnet, an electrically operated starter having a normally open circuit, a switch for

closing the starter circuit, and means whereby the electro-magnet is enabled to close the generator circuit and mechanically prevent the operation of the starter switch.

6. In combination with an electric control system for an explosive engine including a generator and a generator circuit, a switch for the generator circuit, an electrically operated starter having a normally open circuit, a switch for closing the starter circuit, an electro-magnet, and means operated by the electro-magnet for closing the generator circuit switch and mechanically preventing the closing of the starter circuit switch.

7. In combination with an electric control system for an explosive engine including a generator and a generator circuit, an electrically operated starter having a normally open circuit, a switch for closing the starter circuit, an electro-magnet, and an armature therefor acting as a switch to close said generator circuit and mechanically locking the starter switch.

8. In combination with an electric control system for an explosive engine including a generator and a generator circuit, an electrically operated starter having a normally open circuit, a switch for closing the starter circuit, a magnetically operated armature acting as a switch for said generator circuit, said armature having two operative positions in which the starter switch is locked, and in one of which the said generator circuit is closed, and a third position in which the generator circuit is open and the starter switch unlocked.

9. In combination with an automotive vehicle, including an engine, an electric generator, a generator circuit, an electric starting motor, a battery, an electric circuit between said battery and said motor, a switch within said starter circuit, a clutch pedal adapted to move beyond clutch releasing position to close said switch, and electro-magnetically operated means in said generator circuit for preventing motion of said clutch pedal beyond clutch releasing position.

In testimony whereof, I affix my signature.

SOLON J. BOUGHTON.
